UNITED STATES PATENT OFFICE.

OLIVER P. SAMMONS, OF DENISON, TEXAS.

TELEPHONE TRANSMITTER AND RECEIVER.

SPECIFICATION forming part of Letters Patent No. 732,449, dated June 30, 1903.

Application filed July 14, 1900. Serial No. 23,644. (No model.)

To all whom it may concern:

Be it known that I, OLIVER P. SAMMONS, a citizen of the United States, residing at Denison, in the county of Grayson and State of 5 Texas, have invented a new and useful Telephone Transmitter and Receiver, of which the following is a specification.

My invention relates to telephones, and more particularly to repeaters for the same; 10 and it has for its object to produce a device which may be connected with the wires of what are known as "long-distance" telephones for the purpose of taking up the weakened vibrations and reenergizing them, 15 as it were, and transmitting them with increased volume, whereby the ordinary tone of voice may be transmitted any desired distance by simply providing the wires over which it is transmitted with a sufficient number 20 of my improved repeaters to take up the weakened vibrations and send them forward with increased energy and volume.

With these objects in view my invention consists in the improved construction and 25 novel arrangement of parts of a telephone-repeater, as will be hereinafter more fully set forth.

In the accompanying drawing, which is a diagrammatic view, partly in section, I have 30 shown one form of embodying my invention.

In the drawing, 1 and 2 indicate the ordinary wires of a metallic circuit and which may extend between any two desired points of conversation and be provided with any 35 ordinary instruments at the ends, which form no parts of my invention and are therefore not shown in the drawing. Located at suitable distances along the line are one or more repeaters, each of which is preferably mounted 40 upon a base 3 and inclosed within a suitable sound-proof box or casing 4.

Located within the box 4 is a receiver 5 and a transmitter 6. The diaphragm 7 of the receiver is supported upon shoulders 8 adjacent 45 to the end of its casing, and the diaphragm 9 of the transmitter is correspondingly supported upon shoulders 10, said shoulders being preferably insulated from their casings. The two casings are arranged 50 as close together as possible, so as not to be in actual contact, and communicate with each other through a suitable tube or con-

duit 11. The usual convexed carbon back 12 is secured, adjustably or otherwise, adjacent to the diaphragm 9 upon shoulders 13, 55 which are also insulated from the casing. Loose or granular carbon 14 is arranged between the diaphragm 9 and the carbon back 12 for assisting in transmitting the electrical current in the usual manner. One or more 60 permanent magnets 15—preferably two—are located within the receiver, with the poles adjacent to the diaphragm 7, and are each provided with wires 16, which lead to binding-posts 17 upon the base, through which 65 connection may be made with the wires 1 and 2 by means of branch wires 18. An induction-coil 19 is secured upon the base, and the terminals of the secondary coil are connected with binding-posts 20, through which 70 connection may be made with the wires 1 and 2 by means of the branch wires 21. The other end of one of the wires 22 of the induction-coil is connected with the diaphragm 9, and the other end of the other wire 23 is 75 connected with a battery 24. The other wire 25 of the battery is connected with the carbon back 12.

If desired, the branch wires 18 and 21 may be provided with the usual fuses 26 or other 80 safety appliance to prevent injury to the instruments.

Instead of connecting the repeaters to the line in multiple, as shown in the drawing, they may be connected with a single line by 85 simply running one of the branch wires to the ground in the usual manner. The box may be rendered sound-proof in any desired manner, as by forming the exterior casing larger than the casings of the transmitter 90 and receiver and filling the space with plaster-of-paris or other non-combustible or non-sound-transmitting material.

As above described, it is evident that by using my improved repeater the sound of the 95 voice can be transmitted to any desired distance, as all that is necessary is to provide the main line with one or more repeaters at such points as will be necessary to take up the feeble or weakened vibrations in the receiver and transmit them to the diaphragm of the receiver, where they will effect the electrical circuit of the local battery in such manner as to be transmitted from that point 100.

with increased power and energy. In this manner they can be reenergized or increased in volume as many times as desired to send them any distance whatever by simply passing them through my improved transmitter. In this manner a great saving can be effected by using less expensive wires, and a much more satisfactory result can be secured by increasing the volume or the amplitude of the vibrations at the final receiver, whereby the conversation is rendered much more distinct than with instruments now in use. As the apparatus is entirely automatic, it will not require the attention of an assistant except to occasionally renew the strength of the local batteries.

Having thus fully described my invention, what I claim as new, and desire to secure by Letters Patent, is—

- 20 1. In a telephone-repeater, the combination with the base having a sound-proof box, of a receiver arranged within the box, and a transmitter arranged also within the box, a conduit connecting the receiver and transmitter, the diaphragms being adjacent to the ends of the conduit, an induction-coil and a battery connected with the transmitter, all arranged and adapted to operate, substantially as described.
- 25 2. In a telephone-repeater, the combination with a sound-proof casing divided into com-

partments, a receiver in one compartment, a transmitter in the other compartment, a conduit connecting said compartments, said receiver comprising a diaphragm mounted and insulated from the casing at one end of said conduit, electromagnets having their poles in proximity to said diaphragm, a branch circuit from the main line, divided circuits from one wire of said branch circuit connected with one terminal of each of said magnet-coils, and divided circuits from the other wire of said branch circuit connected with the other terminals of said magnet-coils, said transmitter comprising a diaphragm mounted and insulated from the casing at the other end of said conduit, opposite said receiving-diaphragm, a carbon back in proximity to said diaphragm and granular carbon particles interposed between said diaphragm and said carbon back, the primary coil of an induction-coil connected at one terminal with said carbon back, a source of electricity being in said circuit, and at the other terminal with said diaphragm, and a communicating line 55 or circuit attached to the terminals of said secondary coil and to the main line, substantially as described.

OLIVER P. SAMMONS.
